UNITED STATES PATENT OFFICE

BEN L. MALKIND, OF LONG ISLAND CITY, NEW YORK

KNITTING NEEDLE

Application filed March 21, 1932. Serial No. 600,350.

This invention relates to improvements in knitting needles and has particular reference to a holder therefor.

The primary object of the invention resides in a holder for knitting needles for the mending of runs in stockings or other knitted fabrics and is of the well known type embodying a body member having a hook on one end thereof and a latch member pivoted 5 to said body member, the free ends of the latch member being adapted to fly up and down as the needle is moved forward and backward through the fabric under repair, thus opening and closing the hook to knit 10 the ladder threads of the runs. Great difficulty has been experienced in the use of such needles as it is possible for an expert operator to pick up two or more ladder threads at a time instead of a single thread even 15 though proceeding at a slow speed, thus an imperfect repair job results therefrom. My improved holder embodies means for limiting the forward movement of the needle to prevent more than one cross thread from 20 being picked up on each operation which enables an unskilled person to rapidly actuate the needle without fear of producing imperfect chain stitches.

Another object of the invention is to provide a knitting needle holder for receiving 25 and holding knitting needles of different sizes and in which the needle receiving end is formed with a nose for abutting engagement with the ladder thread for limiting the forward movement of the needle to cause the hook thereof to engage a single thread on each actuation thereof.

A further object is the provision of a knitting needle holder which is constructed of a single blank of bendable metal, bent into substantially pear shape in cross section to provide a pair of resilient inner clamping walls for the reception and gripping of the needle to be held, and opposed rounded outer walls 40 to permit the fingers of the hand of an operator to comfortably grip the holder when in manual use.

With these and other objects in view, the invention resides in the certain novel construction, combination and arrangement of

parts, the essential features of which will be hereinafter fully described, are particularly pointed out in the appended claims, and are illustrated in the accompanying drawing in which:

Figure 1 is a top plan view of my improved knitting needle holder showing a knitting needle supported therein.

Figure 2 is a side elevational view thereof. Figure 3 is a front elevational view with the knitting needle removed.

Figure 4 is an enlarged vertical transverse sectional view on the line 4—4 of Figure 2.

Figure 5 is a fragmentary side elevational view showing one position of the holder when in use.

Figure 6 is a vertical longitudinal sectional view showing the stop nose of the holder in abutting engagement with one of the ladder threads for limiting forward and downward movement of the holder when in use.

Figure 7 is an enlarged vertical transverse sectional view on the line 7—7 of Figure 5.

Figure 8 is a fragmentary top plan view of a slightly modified form of construction.

Figure 9 is a side elevational view of the form shown in Figure 8.

Referring to the drawing by reference characters, the numeral 10 designates my improved knitting needle holder in its entirety and in Figures 1 to 7 inclusive, the said holder is constructed of a single blank of bendable metal to provide an elongated body 11. The body 11 is substantially pear shape in cross section as shown in Figure 4 of the drawing and is formed by bending the single blank of material centrally of its length to provide a pair of flat inner resilient walls 12—12 which are diametrically recessed to provide coacting clamping jaws 13—13 while the said blank material is further bent outwardly and downwardly to provide outer rounded or curved side walls 14—14 which meet between the central fold of the blank as shown in Figures 3 and 4 of the drawing. The outer walls 14—14 bulge outwardly and impart a pear or heart shape to the body 11 in cross section.

The forward end of the body member 11 is provided with a forwardly extending nose 15 which is disposed above, and which extends

slightly below the plane of the longitudinal axis of the clamping jaws 13-13 and designated in Figures 2 and 3, and which nose is formed by cutting away the forward ends of the outer side walls 14-14 as at 16 and also cutting out the adjacent ends of the inner walls 12-12 as at 17. The cutaway portion 16 of the outer wall is set back from the cutaway portion 17 of the inner wall and both cutaway portions constitute a graceful compound curve for a purpose to be presently explained. The nose 15 is slotted as at 18, the side walls of which flare outwardly in opposite directions as at 19 to accommodate the latch of the knitting needle when in position within the holder as will now be explained. The front face of the nose 15 is concaved to provide a seat for the abutment of the ladder thread and which prevents the next adjacent ladder thread from riding under the nose and over the latch in the open position in the same manner as that in which the loop is formed thus preventing an imperfect stitch.

25 The conventional form of knitting needle is shown by the reference numeral 20 and includes an elongated shank 21, one end of which terminates in a hook 22, while pivoted to the shank adjacent the open end of the hook is a pivoted latch 23 which is alternately movable into engagement with the hook for opening and closing the same during a knitting operation. When the knitting needle is attached to the holder 11 by the insertion of the shank 21 between the resilient jaws 13-13, the hook end is disposed adjacent the nose 15 as shown in the drawing while the slot 18 above accommodates the backward movement of the latch 23 when moved to open position.

40 The workings of a knitting needle of the type shown is well known in the art and it is not believed necessary to go into the details of the operation of the same but the general operation will be mentioned to bring out the advantages of my holder in connection therewith during use. It will be appreciated that the fabric A to be repaired is first placed under a slight tension whereupon the hook end 22 of the needle is forced into the fabric A just back of one of the last loops of the run or ravelling after which the tension on the fabric is increased. The needle and holder are then pushed downwardly so that the loop 55 B slips over the hook and also over the latch 23 with the latch in a backward open position and rides back onto the shank to clear the latch. Upon the upward stroke, the latch moves to a closed position to cast the loop over the hook, and in the interim the hook has picked up the next adjacent ladder thread for forming the next loop. On the downward stroke, the nose 15 of the holder abuts the ladder thread C, thus limiting the forward and downward movement of the needle

to prevent the hook 22 from engaging more than a single ladder thread on each pickup operation. By limiting the forward and downward stroke of the needle, a more rapid operation may be produced without fear of the hook 22 grasping more than a single ladder thread on each pickup stroke. This is believed to be a decided advantage over the prior type of knitting needle wherein no means are provided for limiting the length of the stroke, thus an operator was obliged to work slowly in order to avoid producing improper chain stitches during the repair of runs or ravelling in knitted fabrics.

70 By constructing the holder member in the manner described, it is possible to insert needles of various sizes into the jaws 13 which may be accomplished by either forcing the shank of the needle therein or by inserting a knife or like implement between the top portions of the inner side walls 12 to spread the jaws to accommodate the size of the needle shank.

75 In Figures 8 and 9 of the drawing the same principle is involved but in this form I provide a solid body 11', the forward end of which is cut away as at 16' to form a forwardly extending nose 15' in which an inwardly extending slot 18' is provided for the reception of the latch of the needle supported in the body 11' by insertion of the same into a bore 13' provided axially therein. This form of holder may be used in knitting machines wherein means are provided for imparting reciprocation to the holder during 80 knitting operation in lieu of manual use of the holder as shown in the preferred form in Figures 1 to 7 inclusive.

90 It might be mentioned that the cutaway portions 16 and 17 in the preferred form 95 and 16' in the modified form provide a clearance for the forward ends of the holder to prevent the same from contact with the knitted fabric during the knitting operation. In the preferred form the curved edges of the 100 cutaway portion of the walls serve to strengthen the walls of a slot 18 to prevent accidental disalignment of the walls which would interfere with the free movement of the latch and loop threads during a knitting operation.

105 While I have shown and described what I deem to be the most desirable embodiment of my invention, it will be understood that various details in construction may be resorted to if desired and I do not limit myself to the exact details shown nor to anything less than the whole of my invention limited only by the appended claims.

110 I claim:

115 1. In combination, a holder element including an elongated handle having a socket in the forward end thereof, a knitting needle having a shank extending in the said socket, a portion of the forward end of said handle

cut away to provide a nose disposed above and slightly below the plane of the axis of said socket to act as a stop and the outer face of said nose being concaved for abutting engagement with the ladder threads of a ravel or run in a piece of knitted fabric for limiting forward movement of the needle to prevent picking up of more than one ladder thread on each complete actuation of the

5 needle during use of the same.

2. In combination, a holder element including an elongated handle having a socket in the forward end thereof, a knitting needle having a shank extending in the said socket, a portion of the forward end of said handle cut away to provide a nose disposed above the plane and slightly below the axis of said socket to act as a stop for abutting engagement with the ladder threads of a ravel or

15 run in a piece of knitted fabric for limiting forward movement of the needle to prevent picking up of more than one ladder thread on each complete actuation of the needle during use of the same, and a slot provided in

20 said nose, the walls of which flare outwardly to accommodate the latch of said needle upon its backward movement.

3. A knitting needle holder comprising an elongated handle member constructed of a single length of bendable metal, bent upon itself along its longitudinal center to provide a pair of resilient clamping walls having opposed recesses therein, the metal being bent to provide outwardly curved side walls enclosing said inner clamping walls, the inner and outer walls being cut away at one end to provide a nose, substantially as and for the purpose specified.

40 Signed at New York city, in the county of New York and State of New York, this 4th day of March, A. D. 1932.

BEN L. MALKIND.
